UNITED STATES PATENT OFFICE.

OLIVER B. DOBBINS, OF CHAMPAIGN, ILLINOIS.

AUTOMATIC CLOSURE-OPERATING DEVICE.

Application filed February 10, 1926. Serial No. 87,350.

The present invention relates to improvements in closure operating devices and has reference more particularly to an automatic means for opening and closing a movable closure by the action of the wheels of a vehicle.

One of the important objects of the present invention is to provide a highly novel, yet simple device whereby a movable closure may be opened and closed by the wheels of the vehicle approaching and passing through the entrance with which the closure is associated, thus saving considerable time and labor, and furthermore obviating the necessity of the operator of the vehicle having to leave the same and manually actuate the closure.

A further object is to provide a device of the above mentioned character which will at all times be positive and efficient in its operation, the same being further simple in construction, inexpensive, strong and durable and further well adapted to the purpose for which it is designed.

Other objects and advantages of the invention will become apparent during the course of the following description taken in connection with the accompanying drawings.

In the accompanying drawings forming a part of this application and in which like numerals designate like parts throughout the same:—

Figure 1 is a side elevation showing the device as associated with an upwardly swinging gate and the means arranged in the roadway on either side of the gate for controlling the opening and closing of the gate.

Figure 2 is a top plan view thereof.

Figure 3 is an elevational view of the gate and the actuating mechanism associated therewith.

Figure 4 is a top plan view of the modification showing the device associated with a sliding door, and

Figure 5 is an enlarged fragmentary detail thereof illustrating the sliding door operator more fully.

In the drawings wherein for the purpose of illustration is shown the preferred embodiment of my invention, the numeral 1 designates generally the gate, the same being pivotally supported at its lower inner end on the pivot pin 2 which extends transversely through the lower portion of a pair of spaced vertical standards 3 and 4 respective-

ly, which standards form the gate posts. The standards of the gate post are spaced a sufficient distance apart so as to permit the gate to swing upwardly between the standards without any difficulty. As is clearly shown in Figure 1, the standard 3 extends above the standard 4.

The gate post 5 formed by the spaced standards 3 and 4 is preferably arranged at one side of the road and arranged at the opposite side of the road directly opposite the gate post 5 is the post 6, the same cooperating with the free end of the gate to limit the lateral movement of the gate.

Jounaled transversely through the upper end of the standard 3 is the shaft 7. A ratchet wheel 8 is fixedly secured on the outer end of the shaft and is spaced from the outer face of the standard 3 in the manner as is more clearly illustrated in Figure 1 of the drawings. The inner end of the shaft 7 terminates in the laterally extending arm 9, and the same is disposed adjacent the inner face of the standard 3. The purpose of this arm will be hereinafter more fully described.

A lever 10 is loosely mounted at its inner end on the outer end portion of the shaft 7, and is disposed between the outer face of the standard 3, and the adjacent face of the ratchet wheel 8. A pivoted pawl 11 is carried by the intermediate portion of the lever 10 and the same cooperates with the ratchet teeth formed in the peripheral edge of the ratchet wheel 8 for actuating the shaft as will also hereinafter be more fully described. A dog 12 is secured on the outer face of the upper portion of the standard 3 and also cooperates with the ratchet teeth of the ratchet wheel in preventing the rotation of the shaft in the reverse direction.

A retractile coil spring 13 is secured at its lower end to the outer end of the lever 10, the upper end of the coil spring being secured to the outer end of the bracket 14 which is secured on the upper end of the standard 3 of the gate post 5 and extends laterally therefrom. A similar coil spring 15 is connected at one end to the outer end of the arm 9, the other end of the coil spring 15 being secured to the gate 1 as is clearly shown in Figure 3.

An elongated beam 16 is pivotally secured at its inner end to the gate 1 as at 17, the beam extending rearwardly between the spaced standards 3 and 4 forming the gate

post 5 and carrying at its outer end the counter weight 18. A lateral projection 19 is formed on the rear end of the gate adjacent the upper end thereof and provides a support for the inner pivoted end of the beam for normally holding the beam in its upwardly inclined position when the gate is closed, as is also clearly shown in Figure 3.

A pair of cables or other flexible members indicated at 20 and 21 respectively are secured at one end to the outer end of the lever 10, these cables extending downwardly adjacent the standard 3 and being trained over suitable pulleys 22 and 23 respectively, which are supported on the rear side of the standard 3 adjacent the lower end thereof, the cables extending laterally in opposite directions along the side of the road.

A pair of relatively short posts or blocks indicated at 24 and 25 respectively are set in the roadway a suitable distance from the gate 1 on one side thereof, a similar pair of blocks or posts indicated at 26 and 27 being arranged on the opposite sides of the gate at a similar distance therefrom. The blocks 24 and 26 are preferably arranged adjacent the side of the road while the other blocks 25 and 27 extend upwardly from the road bed in the intermediate portion thereof and preferably at such a distance with respect to the blocks 24 and 26 respectively so as to enable at least one pair of aligned front and rear wheels of the vehicle to pass between the spaced blocks or posts of each pair. The outer end of the cable 20 is trained under a suitable pulley 28 which is secured on the outer side of the block 24 adjacent the bottom thereof. The cable then extending upwardly along the outer side of the block and being trained over an additional pulley 29 which is mounted on the top of the block. The end of the cable 20 is secured to one end of the trip member 30 which in the present instance is in the form of a chain, the other end of the chain being secured to the top of the block 25.

In a similar manner, the outer end of the other cable 21 is trained under a pulley 31 which is secured on the outer side of the block 26 adjacent the bottom thereof. The cable 21 being then trained over an additional pulley 32 mounted on the top of the block 26 and being secured to a similar trip member 33 at one end thereof, the other end 55 of the chain forming the trip member 33 being secured to the top of the block 27. This construction is thought clearly illustrated in Figures 1 and 2 of the drawings.

The blocks or posts which are arranged in the roadway are of such height as not to interfere with the passing of the vehicle thereover and furthermore the trips 30 and 33 are normally held taut through the medium of the retractile coil spring 13 which also holds the lever 10 in its normal position.

With the parts arranged as above described, and the gate 1 in its normally closed position, when the vehicle approaches the gate and is traveling in the direction of the arrow, as soon as the outer front wheels 70 of the vehicle passes over the chain 30, the trip will be depressed, and will simultaneously cause an outward pull to be exerted on the cable 20 which will result in the downward swinging movement of the lever 75 10 against the tension of the spring 13 and the pawl 11 carried by the lever 10 will turn the ratchet wheel and the shaft 7 on which said ratchet wheel is fixed, a quarter of a revolution. The rear outer wheel of the vehicle will further effect the rotation of the shaft another quarter of a revolution when said wheel passes over the trip chain 30.

When the shaft has completed a half of 85 a revolution, the gate 1 will in the mean time have swung upwardly on its pivot 2 to the position shown in the dotted lines in Figure 3, the arm 9 in the coil spring 15 assisting in the upward and rearward swinging movement of the gate as well as the beam 16 in the counter weight 18. A stop such as is shown at 34 cooperates with the beam 16 in limiting the downward swinging movement thereof so that the gate will be maintained in such a position as to enable the same to be closed in the manner to be presently described.

When the gate is opened, the vehicle is free to pass through the entrance normally 100 closed by the gate and the gate 1 will be returned to its normally closed position in the same manner as the same was swung to an open position, by causing the outer front and rear wheels of the vehicle to pass over the trip chain 33 whereupon the cable 21 will be pulled outwardly to further effect the actuation of the lever 10 so that when both the front and rear outer wheels of the vehicle have passed over the trip 33, the 110 shaft 7 will have completed a whole revolution and the expanded retractile spring 15 will automatically return the gate to its closed position.

The provision of a gate operating structure of the character above described will enable the gate to be automatically opened and closed by a vehicle without necessitating the operator of the vehicle having to leave the car in order to open or close the 120 gate, thereby saving considerable time and labor.

My improved closure operator may also be associated with garage doors, either of the swinging, sliding, or tilting type in the 125 same manner as the device is associated with a swinging gate, and in Figures 4 and 5 of the drawings, I have illustrated the device as being associated with the sliding door. The device as associated with the sliding 130

door A includes the same lever and ratchet mechanism as heretofore shown and described, the shaft 7 on which the ratchet wheel 8 is fixed extending through the wall 5 of the building or garage in which the door opening is formed. An arm 9 is fixed at its outer end on the shaft 7, the inner end of said arm being provided with an eye 35 which is interconnected with the eye 36 10 formed on the outer end of the elongated tubular member 37, the outer end of the tubular member being closed, while the inner end is open.

Adapted for slidable movement within 15 the tubular member 37 is an additional tubular member 38, the same being hingedly secured at its outer end to the sliding door 8, as at 39. Each of the tubular telescopic members is slotted longitudinally as indicated at 40 and 41 respectively. A retractile coil spring 42 encircles the inner portion 20 of the larger tubular member 37, one end of the coil spring extending into the slot 40, and being disposed adjacent the inner end of the slot, the other end of the coil spring extending into the other slot 41 25 formed in the inner tubular member 38 and being disposed adjacent the inner end of said slot.

30 An actuating cable 43 is connected to the outer end of the pivoted lever 10 and is trained over suitable pulleys mounted on the front of the building or garage, and the outer end of the cable is connected to a suitable trip mechanism similar to that heretofore shown and described, and which is arranged on the outside of the door opening a suitable distance therefrom.

The operation of the ratchet mechanism is 40 identical with that provided for actuating the swinging gate 1, and manifestly when the shaft 7 has made a one half revolution, the door A will have moved to an open position through the medium of the expansion 45 of the coil spring 42. When the other one-half revolution has been completed, the coil spring 42 will effect the sliding movement of the door A to a closed position, and this is readily obvious from the construction of 50 the telescopic tubular member, and the arrangement of the ends of the coil spring 42 with respect to said tubular member.

While I have shown the preferred embodiment

of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. In combination with a movable closure, and its support, of a shaft journaled in said support, a ratchet wheel secured on said shaft, an arm fixed on said shaft, a resilient connection between said arm and the movable closure, a pivotally mounted lever, a pawl carried thereby and adapted for engagement with the ratchet wheel for effecting the rotation of the shaft, and the simultaneous movement of the closure, and a cable for actuating said lever.

2. In combination, a gate post, and an upwardly swinging gate pivoted thereto, a shaft journaled transversely through the upper portion of the post, a ratchet wheel fixedly secured on one end of the shaft, an arm extending laterally from the other end of the shaft, a retractile coil spring connecting said arm with said gate, a pivotally mounted lever, a pawl carried thereby and adapted for engagement with the ratchet wheel to effect the rotation of the shaft and the expansion of the coil spring whereby said gate is caused to swing on its pivot, and means for actuating the lever from a remote point.

3. In combination, a gate post, and an upwardly swinging gate pivoted thereto, a shaft journaled transversely through the upper portion of the post, a ratchet wheel fixedly secured on one end of the shaft, an arm extending laterally from the other end of the shaft, a retractile coil spring connecting said arm with said gate, a pivotally mounted lever, a pawl carried thereby and adapted for engagement with the ratchet wheel to effect the rotation of the shaft and the expansion of the coil spring whereby said gate is caused to swing on its pivot, means for actuating the lever from a remote point, and means for returning the lever to its normal position.

In testimony whereof I affix my signature.
OLIVER B. DOBBINS.
